(22) Filed: **Nov. 15, 2012**

Primary Examiner — Mitchell Siegel
(74) Attorney, Agent, or Firm — Klarquist Sparkman, LLP

(51) LOC (10) Cl. 21-02

(57) **CLAIM**

(52) U.S. Cl. 21/759

We claim the ornamental design for a golf club head, as shown and described.

(58) Field of Classification Search

DESCRIPTION

USPC D21/733, 752, 759; 473/324-331,
473/343-346

See application file for complete search history.

FIG. 1 is a perspective view of a golf club head, as viewed from the rear and one side, according to one embodiment. FIG. 2 is a front elevation view of the golf club head of FIG. 1.

(56) **References Cited**

FIG. 3 is a rear elevation view of the golf club head of FIG. 1. FIG. 4 is a side elevation view of the heel side of the golf club head of FIG. 1

U.S. PATENT DOCUMENTS

FIG. 5 is a side elevation view of an opposite toe side of the golf club head of FIG. 1.
